(57) **CLAIM**

The ornamental design for a glove with a stethoscope pocket, as shown and described.

DESCRIPTION

FIG. 1 is a front elevation view of a glove with a stethoscope pocket, which embodies my design;

FIG. 2 is a side elevation view of the glove with a stethoscope pocket;

FIG. 3 is an opposite side elevation view of the glove with a stethoscope pocket;

FIG. 4 is a bottom plan view of the glove with a stethoscope pocket;

FIG. 5 is a top plan view of the glove with a stethoscope pocket; and,

FIG. 6 is a side perspective view of the glove with a stethoscope pocket showing my new design in a position of use. The broken line showing of a stethoscope in FIG. 6 illustrates environmental subject matter and forms no part of the claimed design.
